Patented Oct. 27, 1908.

2 SHEETS—SHEET 2.

UNITED STATES PATENT OFFICE.

WALTER C. BECKWITH, OF FOSTORIA, OHIO.

PUMPING APPARATUS FOR OIL-WELLS.

No. 902,469.

Specification of Letters Patent.

Patented Oct. 27, 1908.

Application filed January 17, 1908. Serial No. 411,265.

To all whom it may concern:

Be it known that I, WALTER C. BECKWITH, a citizen of the United States, residing at Fostoria, in the county of Seneca and State of Ohio, have invented certain new and useful Improvements in Pumping Apparatus for Oil-WellS, of which the following is a specification, reference being had therein to the accompanying drawing.

10 My invention relates to improvements in pumping apparatus for oil wells.

The object of my invention is to provide a pumping apparatus of this character, which does away with the polish rod, and its packing, and also with the usual jack, which produces a much more simple, and effective pump, thus doing away with the frequent re-packing of the polish rod.

Another object of my invention is to provide a pump of this character, in which the sucker rod can be readily removed without disturbing the packing of the working part of the pump.

A still further object of my invention is to provide a more simple, cheap and effective pump to accomplish the above results.

In the accompanying drawings, Figure 1, is a side elevation of my improved pumping apparatus. Fig. 2, is a vertical longitudinal 30 sectional view showing the pulley wheel or drum in full lines. Fig. 3, is a transverse vertical sectional view. Fig. 4, is a side elevation of a modified form of mechanism for operating the pump.

35 Referring now to the drawings, 1 represents the well casing of an oil well, and which usually carries a stuffing box through which the polish rod extends, and works up and down. My invention is designed to obviate the use of this stuffing box, and also the use of the polish rod, and also any packing whatever for the sucker rod.

The invention consists of a casing or housing 2 having a downwardly-extending circular portion 3 having an opening therethrough, and communicating with the housing, and having internal threads 4 by means of which it is screwed upon the upper end of the well casing. The portion 3, as shown in the drawings, is at one side of the housing and forms a support for the housing, and also a communication with the well casing. This portion 3 extends upwardly and forms a vertical space at one side of the casing, as indicated at 3', and which communicates with

the casing, as shown in Fig. 2, and which will be hereinafter more fully described.

The housing, as shown, is made in two sections 5 and 6, the upper section 6, as shown, being removable, and the two sections provided with outwardly-extending abutting flanges 7 and 8 between which a packing 9 is placed for forming a tight housing for the purpose hereinafter set forth.

The sides of the lower sections are provided with openings which are surrounded by stuffing boxes 10 and 11, and passing through the openings in the lower section and through the stuffing boxes, is a shaft 12 which extends out beyond the stuffing boxes. Within the housing on the shaft 12 is a drum or pulley 13 which is of such a diameter that it extends into the vertical passage 3' at the side of the housing. This passage, as shown, is directly over the well casing, and within the casing is the sucker and sucker-rod 14 to which is attached a chain 15 by means of the detachable coupling 16. The upper end of the chain is secured to the outer periphery of the drum 13, as indicated at 16', and by rocking the drum, as will be hereinafter more fully described, the chain will be raised and lowered, and the sucker-rod 14 raised and the weight of the same causes it to drop down, and thus the oil is drawn upwardly within the housing.

The drum 13 has a cut-away portion 17 which when turned around opposite the vertical passage 3' leaves an unobstructed passage, whereby when the upper portion of the housing is removed the sucker-rod and the sucker can be removed without disconnecting any of the working parts, or any of the packing.

The outer ends of the shaft 12 on the outside of the stuffing boxes, are provided with arms 19 and 20 which are keyed upon the shaft and extend upwardly over the housing and are drawn inwardly, as indicated at 21 and 22, to bring the upper ends thereof closer together. Between the upper ends of these arms are secured the shackle rod 23 to which is imparted a reciprocating movement which rocks the arms 19 and 20, and oscillates the drum for working the pumping apparatus, as heretofore described.

The stuffing boxes 10 and 11 around the shaft are for making a tight joint therewith, as the housing is filled with oil, and thus prevents the waste of any oil. The housing is

provided with a discharge pipe 24 from which the oil is conveyed to the desired point and may be connected to the casing at any desired point.

5. The housing at the opposite end to which is attached the well casing is provided with feet 25 which more rigidly support the casing.

In Fig. 4 instead of having the arms 19 and 20 extending upwardly, I provide downwardly-extending arms 26 provided with a series of openings 27 by means of which the forked member 28 is secured thereto, and by attaching said forked members at different points on the arms 26 the movement of the drum is varied and thus the throw of the sucker rod is regulated.

By the construction herein shown and described, it will be seen that through the medium of the drum 13 and chain 15 there is a 20 straight vertical pull upon the sucker-rod. There being no polish rod, and also no packing for the sucker-rod, when it is desired to remove the same none of the working parts of the pump have to be disturbed, but it is 25 only necessary to remove the section 6 of the casing and turn the drum 13 around so that the cut-away portion 17 is around opposite the passage 3'.

Having thus described my invention, what 30 I claim and desire to secure by Letters Patent, is:—

1. The combination with a well casing, a piston rod therein, a tight housing secured upon the upper end of the casing, a drum 35 within the casing and having a flexible connection with the piston rod, and said drum having a cut-away portion in its periphery, whereby the piston rod may be removed through the housing without disturbing the drum.

2. The combination with a well casing, a piston rod therein, a tight housing secured upon the upper end of the casing at one side, a drum within the casing and its outer periphery 45 extending over the center of the well casing, a flexible connection between the drum and piston rod, and said drum having a cut-away portion in its periphery, whereby the piston can be removed through the housing without disturbing the working parts of the drum.

3. The combination with a well casing, of a tight housing secured upon the upper end of the casing, a shaft extending through the 55 housing, a drum carried by the shaft within the housing, a sucker-rod within the casing, a chain having one end secured to the outer periphery of the drum and the other end secured to the sucker rod, and means carried by the shaft on the outside of the housing for rocking the same, the said drum having a cut-away portion which can be brought over the well-casing for removing the pump-piston therefrom.

4. The combination with a well casing, of

a tight housing secured upon the upper end of the casing, a shaft extending through the housing, a drum carried by the shaft within the housing, the outer periphery of which is directly over the center of the well-casing, a 70 sucker-rod within the casing, and a chain having one end connected to the periphery of the drum and the opposite end connected to the sucker rod the said drum having a cut-away portion which can be brought over the 75 well-casing for removing the pump-piston therefrom.

5. The combination with a well casing, of a tight housing formed in two sections and having its lower end at one side, a shaft 80 mounted in the lower section and extending through the sides thereof, stuffing boxes carried by the housing and surrounding the shaft, a drum carried by the shaft within the housing and having a cut-away portion, a 85 flexible connection between the drum and sucker rod, and means for operating the shaft.

6. The combination with a well casing, of a tight housing secured to the said casing, a shaft extending through said housing, a 90 drum carried by the shaft and having its outer periphery directly over the well casing, the said drum having one side cut away to form a vertical passage directly over the casing, substantially as set forth.

7. The combination with a well casing, of a housing having a tubular vertical passage at one end, and to which is secured the well casing, a shaft extending through the casing, a drum carried by the shaft within the housing and extending into the vertical passage, a sucker-rod within the well casing, a chain having one end secured to the periphery of the drum and the other end connected to the sucker-rod, a discharge pipe in communication with the housing, and said drum having a cut-away portion in its outer periphery whereby the piston may be removed through the housing.

8. The combination with a well casing, of a tight housing secured to the said casing, a drum carried by the casing and having a cut-away portion which can be brought over the well casing for removing the pump piston from the casing.

9. The combination with a well casing, of a housing having a tubular vertical passage at one end and to which is secured the well casing, and in communication with the housing, an oscillating member within the housing and extending into said vertical passage, and having one side cut away, a sucker rod within the casing and a chain connected between the oscillating member and the sucker rod.

10. The combination with a well-casing, of a housing having a tubular vertical passage at one end and extending below the lower end of the housing and screwed upon the well-casing, a drum within the housing and

extending within the passage, a piston-rod within the casing, a chain connection between the drum and the piston-rod, and the drum having a cut-away portion which can 5 be brought within the vertical passage for removing the piston-rod from the casing.

11. The combination with a well-casing, of 10 a housing formed in two sections, the upper section removable, a shaft extending transversely through the lower section, said lower section having a vertical tubular passage at one side and forming an extension of the housing and said extension screwed upon the well casing, a drum mounted upon the shaft 15 within the housing, and extending within the

passage, a piston-rod within the casing, a flexible connection between the drum and the piston-rod, and the drum having a cut-away portion which can be brought within the vertical passage for removing the piston-rod 20 from the casing, and arms carried by the shaft on the outside of the casing for operating the drum.

In testimony whereof I affix my signature in presence of two witnesses.
